(57) **ABSTRACT**

A display apparatus includes a data driver, a demux circuit, a wire mixing structure and a display panel. The data driver includes four output amplifiers. The demux circuit is connected to the four output amplifiers and branches the four output amplifiers into first, second, third, fourth, fifth, sixth, seventh, and eighth output lines through demux switching. The wire mixing structure is connected to the demux circuit, and has an input terminal and an output terminal. The display panel includes data lines connected to the wire mixing structure. When first data is provided to the input terminal of the wire mixing structure in an order of 1, 2, 3, 4, 5, 6, 7 and 8, second data at the output terminal of the wire mixing structure is output in an order of 4, 1, 2, 3, 7, 6, 5 and 8.

PRIORITY STATEMENT

This application claims priority, under 35 U.S.C. § 119, to Korean Patent Application No. 10-2023-0197367 filed on Dec. 29, 2023 in the Korean Intellectual Property Office KIPO, the contents of which are herein incorporated by reference in their entireties.

BACKGROUND

1. Field

Embodiments of the present inventive concept relate to a display apparatus and an electronic apparatus including the display apparatus. More particularly, embodiments of the present inventive concept relate to a display apparatus including a wire mixing structure to enhance demux coupling and prevent data mapping error, and an electronic apparatus including the display apparatus.

2. Description of the Related Art

Generally, a display apparatus includes a display panel and a display panel driver. The display panel displays an image based on input image data. The display panel includes a plurality of gate lines, a plurality of data lines and a plurality of pixels. The display panel driver includes a gate driver, a data driver and a driving controller. The gate driver outputs gate signals to the gate lines. The data driver outputs data voltages to the data lines. The driving controller controls the gate driver and the data driver.

The display panel driver may include a demux circuit for dividing R-G data of the data driver into R data and G data and dividing B-G data of the data driver into B data and G data. In the display apparatus including the demux circuit, a display quality may be reduced due to coupling between a data line outputting the R data or the B data and a data line outputting the G data.

In addition, the data driver may be formed in a border reduction structure in which a data voltage applied to a data line at a center of the display panel and a data voltage applied to a data line at an edge of the display panel are alternatively outputted to reduce a dead space of the display apparatus. In this border reduction structure, lines may be added to transfer data voltages to data lines at the edge. In doing this, and display quality may be reduced due to coupling between the added lines and the data lines.

In addition, the demux circuit may be disposed adjacent to an integrated circuit of the data driver to reduce the dead space of the display apparatus. In this case, the number of wires floating on the display panel further increases so that the display quality may be further reduced due to additional coupling.

In addition, when the output of the conventional data driver is connected to the data line of the display panel, a data mapping error may occur in which the R data or the B data are applied to a G pixel or the G data are applied to a R pixel or a B pixel due to the position shift of the demux circuit.

SUMMARY

Embodiments of the present inventive concept provide a display apparatus including a wire mixing structure to enhance demux coupling and prevent a data mapping error.

2

Embodiments of the present inventive concept also provide an electronic apparatus including the display apparatus.

In an embodiment of a display apparatus according to the present inventive concept, the display apparatus includes a data driver, a demux circuit, a wire mixing structure and a display panel. The data driver includes four output amplifiers. The demux circuit is connected to the four output amplifiers and branches the four output amplifiers into first, second, third, fourth, fifth, sixth, seventh, and eighth output lines through demux switching. The wire mixing structure is connected to the demux circuit, and has an input terminal and an output terminal. The display panel includes data lines connected to the wire mixing structure. First data being provided to the input terminal of the wire mixing structure in the order of 1, 2, 3, 4, 5, 6, 7 and 8 produces second data at an output terminal of the wire mixing structure in an order of 4, 1, 2, 3, 7, 6, 5 and 8.

In an embodiment, the display apparatus may further include a bending area disposed between the display panel and the data driver. The demux circuit may be disposed between an integrated circuit area of the data driver and the bending area.

In an embodiment, the bending area may include a bending line for folding elements toward a rear surface of the display panel. The display panel may be disposed on a first side of the bending line and the demux circuit and the integrated circuit area are disposed on a second side of the bending line.

In an embodiment, output data from the data driver comprise at least one of normal data that are directly applied to data lines of the display panel, and border reduction data that are applied to data lines of the display panel through border reduction lines.

In an embodiment, wherein the first data having order numbers 1, 2, 3, 4, 5, 6, 7 and 8 includes the first data having order numbers of 1, 2, 5 and 6 being the normal data and the first data having order numbers of 3, 4, 7 and 8 being the border reduction data.

In an embodiment, the first, the fourth, the fifth and the eighth output lines of the demux circuit may be activated by a first switching signal. The second, the third, the sixth and the seventh output lines of the demux circuit may be activated by a second switching signal.

In an embodiment, the input terminal of the wire mixing structure may include first to eighth A pads that are sequentially disposed and output terminal of the wire mixing structure may include first to eighth B pads that are sequentially disposed. The first A pad may be connected to the second B pad. The second A pad may be connected to the third B pad. The third A pad may be connected to the fourth B pad. The fourth A pad may be connected to the first B pad. The fifth A pad may be connected to the seventh B pad. The sixth A pad may be connected to the sixth B pad. The seventh A pad may be connected to the fifth B pad. The eighth A pad may be connected to the eighth B pad.

In an embodiment, the data driver may further include an N+1-th output amplifier, an N+2-th output amplifier, an N+3-th output amplifier, an N+4-th output amplifier, an N+5-th output amplifier, an N+6-th output amplifier, an N+7-th output amplifier and an N+8-th output amplifier. The N+1-th output amplifier may be configured to output data of (N+1)A data line and data of (N+1)B data line. The N+2-th output amplifier may be configured to output data of a dummy data line.

In an embodiment, the N+3-th output amplifier, the N+4-th output amplifier and the N+5-th output amplifier may be inactive for a predefined period.

In an embodiment, the N+6-th output amplifier may be configured to output data of (N+2)A data line and data of (N+2)B data line. The N+7-th output amplifier may be configured to output data of (N+3)A data line and data of (N+3)B data line. The N+8-th output amplifier may be configured to output data of (N+4)A data line and data of (N+4)B data line.

In an embodiment, the data driver may further include an N+1-th output amplifier, an N+2-th output amplifier, an N+3-th output amplifier, an N+4-th output amplifier, an N+5-th output amplifier, an N+6-th output amplifier, an N+7-th output amplifier and an N+8-th output amplifier. The N+5-th output amplifier may be configured to output data of (N+1)A data line and data of (N+1)B data line. The N+2-th output amplifier may be configured to output data of a dummy data line.

In an embodiment, the N+1-th output amplifier, the N+3-th output amplifier and the N+4-th output amplifier may be inactive for a predefined period.

In an embodiment, the N+6-th output amplifier may be configured to output data of (N+2)A data line and data of (N+2)B data line. The N+7-th output amplifier may be configured to output data of (N+3)A data line and data of (N+3)B data line. The N+8-th output amplifier may be configured to output data of (N+4)A data line and data of (N+4)B data line.

In an embodiment, the display panel may include a first power applying line, a 1A data line, a 1B data line, a second power applying line, a third power applying line, a 2B data line, a 2A data line and a fourth power applying line which are sequentially disposed. First color data may be applied to the 1A data line. Second color data may be applied to the 1B data line and the 2B data line. Third color data may be applied to the 2A data line.

In an embodiment, the display panel may include a first color first light emitting area, a second color first light emitting area, a third color first light emitting area, a second color second light emitting area, a third color second light emitting area, a second color third light emitting area, a first color second light emitting area and a second fourth light emitting area. The 1A data line may be connected to the first color first light emitting area and the first color second light emitting area. The 1B data line may be connected to the second color first light emitting area and the second color third light emitting area. The 2B data line may be connected to the second color second light emitting area and the second color fourth light emitting area. The 2A data line may be connected to the third color first light emitting area.

In an embodiment, the third color second light emitting area may be connected to a dummy data line.

In an embodiment, the second color first light emitting area and the second color second light emitting area may be disposed in an 1-1 row. The first color first light emitting area and the third color first light emitting area may be disposed in an 1-2 row adjacent to the 1-1 row. The second color third light emitting area and the second color fourth light emitting area may be disposed in a 2-1 row adjacent to the 1-2 row. The third color second light emitting area and the first color second light emitting area may be disposed in a 2-2 row adjacent to the 2-1 row.

In an embodiment, when third data being provided to an input terminal of the demux circuit in an order of 1, 2, 3, 4, 5, 6, 7 and 8 produces fourth data at an output terminal of the demux circuit in an order of 1, 2, 4, 3, 5, 6, 8 and 7.

In an embodiment of an electronic apparatus according to the present inventive concept, the electronic apparatus includes a data driver, a demux circuit, a wire mixing

structure, a display panel, a driving controller and a processor. The data driver includes four output amplifiers. The demux circuit is connected to the four output amplifiers and branches the four output amplifiers into eight output lines through demux switching. The wire mixing structure is connected to the demux circuit and has an input terminal and an output terminal. The display panel includes data lines connected to the wire mixing structure. The driving controller is configured to control the data driver. The processor is configured to output input image data and an input control signal to the driving controller. First data being provided to the input terminal of the wire mixing structure in an order of 1, 2, 3, 4, 5, 6, 7 and 8 produces second data at an output terminal of the wire mixing structure in an order of 4, 1, 2, 3, 7, 6, 5 and 8.

According to the display apparatus and the electronic apparatus including the display apparatus, the display apparatus may support the four-bundle demux switching structure and include the wire mixing structure for preventing the data mapping error so that the demux coupling may be enhanced and the data mapping error may be prevented.

In addition, the display apparatus may support the four-bundle demux switching structure without changing the integrated circuit of the data driver and the active area of the display panel.

In addition, the data driver may be formed in the border reduction structure in which the data voltage applied to the data line at the center of the display panel and the data voltage applied to the data line at the edge of the display panel are alternatively outputted so that the dead space of the display apparatus may be reduced.

In addition, the demux circuit is disposed adjacent to the integrated circuit area on the second side of the bending line so that the dead space of the display apparatus may be further reduced.

In addition, the data driver includes an element for applying the dummy data to the dummy data line so that the proper data may be applied to the dummy data line.

40 BRIEF DESCRIPTION OF THE DRAWINGS

The above and other features and advantages of the present inventive concept will become more apparent by describing in detailed embodiments thereof with reference to 45 the accompanying drawings, in which:

FIG. 1 is a block diagram illustrating a display apparatus according to an embodiment of the present inventive concept;

FIG. 2 is a conceptual diagram illustrating a display panel 50 and a data driver of FIG. 1;

FIG. 3 is a diagram illustrating an example in which coupling occurs in a demux switching structure;

FIG. 4 is a table illustrating an output amplifier of the data driver of FIG. 1 and data mapping of the data driver of FIG. 55 1;

FIG. 5 is a diagram illustrating a data line, a first and a second border reduction line, and a power applying line of the display panel of FIG. 1;

FIG. 6 is a diagram illustrating light emitting areas of the 60 display panel of FIG. 1;

FIG. 7A is a conceptual diagram illustrating an output amplifier of the data driver, a demux circuit, a wire mixing structure and the display panel of FIG. 1;

FIG. 7B is an enlarged conceptual diagram illustrating the 65 wire mixing structure of FIG. 7A;

FIG. 8 is a conceptual diagram illustrating an output amplifier of the data driver for outputting a dummy data to

a dummy data line of the display panel of FIG. 1, the demux circuit and the display panel of FIG. 1;

FIG. 9 is a conceptual diagram illustrating an output amplifier of a data driver for outputting a dummy data to a dummy data line of a display panel of a display apparatus according to an embodiment of the present inventive concept, a demux circuit and the display panel;

FIG. 10 is a block diagram illustrating an electronic apparatus according to an embodiment of the present inventive concept;

FIG. 11 is a diagram illustrating an example in which the electronic apparatus of FIG. 10 is implemented as a smart phone; and

FIG. 12 is a block diagram illustrating an electronic apparatus according to an embodiment of the present inventive concept.

DETAILED DESCRIPTION OF THE INVENTIVE CONCEPT

Hereinafter, the present inventive concept will be explained in detail with reference to the accompanying drawings.

FIG. 1 is a block diagram illustrating a display apparatus according to an embodiment of the present inventive concept.

Referring to FIG. 1, the display apparatus includes a display panel 100 and a display panel driver. The display panel driver includes a driving controller 200, a gate driver 300, a gamma reference voltage generator 400 and a data driver 500.

For example, the driving controller 200 and the data driver 500 may be integrally formed. For example, the driving controller 200, the gamma reference voltage generator 400 and the data driver 500 may be integrally formed. A driving module including at least the driving controller 200 and the data driver 500 that are integrally formed may be referred to as a “timing controller embedded data driver” (TED).

The display panel 100 has a display region AA on which an image is displayed and a peripheral region PA adjacent to the display region AA.

The display panel 100 includes a plurality of gate lines GL, a plurality of data lines DL and a plurality of pixels P connected to the gate lines GL and the data lines DL. The gate lines GL may extend in a first direction D1. The data lines DL may extend in the second direction D2 crossing the first direction D1.

The driving controller 200 receives input image data IMG and an input control signal CONT from an external apparatus. The input image data IMG may include red image data, green image data and blue image data. The input image data IMG may include white image data. The input image data IMG may include magenta image data, yellow image data and cyan image data. The input control signal CONT may include a master clock signal and a data enable signal. The input control signal CONT may further include a vertical synchronizing signal and a horizontal synchronizing signal.

The driving controller 200 generates a first control signal CONT1, a second control signal CONT2, a third control signal CONT3 and a data signal DATA based on the input image data IMG and the input control signal CONT.

The driving controller 200 generates the first control signal CONT1 for controlling an operation of the gate driver 300 based on the input control signal CONT, and outputs the first control signal CONT1 to the gate driver 300. The first

control signal CONT1 may further include a vertical start signal and a gate clock signal.

The driving controller 200 generates the second control signal CONT2 for controlling an operation of the data driver 500 based on the input control signal CONT, and outputs the second control signal CONT2 to the data driver 500. The second control signal CONT2 may include a horizontal start signal and a load signal.

The driving controller 200 generates the data signal DATA based on the input image data IMG. The driving controller 200 outputs the data signal DATA to the data driver 500.

The driving controller 200 generates the third control signal CONT3 for controlling an operation of the gamma reference voltage generator 400 based on the input control signal CONT, and outputs the third control signal CONT3 to the gamma reference voltage generator 400.

The gate driver 300 generates gate signals driving the gate lines GL in response to the first control signal CONT1 received from the driving controller 200. The gate driver 300 outputs the gate signals to the gate lines GL. For example, the gate driver 300 may sequentially output the gate signals to the gate lines GL. For example, the gate driver 300 may be mounted on the peripheral region PA of the display panel 100. For example, the gate driver 300 may be integrated on the peripheral region PA of the display panel 100.

The gamma reference voltage generator 400 generates a gamma reference voltage VGREF in response to the third control signal CONT3 received from the driving controller 200. The gamma reference voltage generator 400 provides the gamma reference voltage VGREF to the data driver 500. The gamma reference voltage VGREF has a value corresponding to a level of the data signal DATA.

In an embodiment, the gamma reference voltage generator 400 may be disposed in the driving controller 200, or in the data driver 500.

The data driver 500 receives the second control signal CONT2 and the data signal DATA from the driving controller 200, and receives the gamma reference voltages VGREF from the gamma reference voltage generator 400. The data driver 500 converts the data signal DATA into data voltages having an analog type using the gamma reference voltages VGREF. The data driver 500 outputs the data voltages to the data lines DL.

FIG. 2 is a conceptual diagram illustrating the display panel 100 and the data driver 500 of FIG. 1.

Referring to FIGS. 1 and 2, the display panel 100 may include the display region AA and the peripheral region PA. The peripheral region PA of the display panel 100 may be connected to a bending area BDA. The bending area BDA may include a bending line BL for folding elements toward a rear surface of the display panel 100. The bending area BDA may be disposed between the display panel 100 and the data driver 500.

The data driver 500 may be formed as a type of a data driving chip DIC. The data driving chip DIC may be disposed on an integrated circuit area ICA of the data driver 500.

The display apparatus may further include a demux circuit DXA. The demux circuit DXA may be disposed between the integrated circuit area ICA and the bending area BDA.

The display panel 100 is disposed on a first side of the bending line BL. The demux circuit DXA and the integrated circuit area ICA may be disposed on a second side of the bending line BL. The demux circuit DXA and the integrated circuit area ICA may be folded toward the rear surface of the display panel 100. In the present embodiment, the demux

circuit DXA is folded toward the rear surface of the display panel 100 so that the dead space of the display apparatus may be reduced compared to a case where the demux circuit DXA is disposed in the peripheral area PA of the display panel 100.

The data driver 500 may have a border reduction structure in which a data voltage applied to a data line (e.g. DL3 and DL4) at a center of the display panel 100 and a data voltage applied to a data line (e.g. DL1 and DL2) at an edge of the display panel 100 are alternatively outputted. The display panel 100 may further include lines BRS1 and BRS2 to transmit the data voltage to the data line (e.g. DL1 and DL2) at the edge of the display panel 100.

FIG. 3 is a diagram illustrating an example in which coupling occurs in a demux switching structure.

Referring to FIGS. 1 to 3, CLA in FIG. 3 indicates a switching signal of a first switch of the demux circuit DXA and CLB in FIG. 3 indicates a switching signal of a second switch of the demux circuit DXA. FIG. 3 illustrates that CLA outputs green pixel data and CLB outputs red and blue pixel data. Alternatively, CLA may output red and blue pixel data and CLB may output green pixel data.

According to an embodiment, a timing GW ON at which the gate signal is turned on may be synchronized with a timing at which CLA maintains a low level or a high level and a timing at which CLB changed from a high level to a low level or from a low level to a high level. Accordingly, when the display panel 100 displays a jagged pattern, the luminance of the green pixel may become brighter (as indicated by a dotted line) due to coupling at the first GW ON timing so that the image may become greenish.

As such, when a data output path synchronized with CLA and a data output path synchronized with CLB are disposed adjacent to each other, a display quality of the display panel 100 may be deteriorated due to data coupling.

FIG. 4 is a table illustrating an output amplifier of the data driver 500 of FIG. 1 and data mapping of the data driver 500 of FIG. 1. FIG. 5 is a diagram illustrating a data line, a first border reduction line, a second border reduction line, and a power applying line of the display panel 100 of FIG. 1. The first border reduction line and the second border reduction extend in nonparallel (e.g., perpendicular) directions. FIG. 6 is a diagram illustrating light emitting areas of the display panel 100 of FIG. 1. FIG. 7A is a conceptual diagram illustrating an output amplifier of the data driver 500, a demux circuit, a wire mixing structure and the display panel 100 of FIG. 1. FIG. 7B is an enlarged conceptual diagram illustrating the wire mixing structure of FIG. 7A.

Referring to FIGS. 1 to 7B, the display apparatus includes the data driver 500, the demux circuit DXA, the wire mixing structure and the display panel 100. In the present embodiment, the demux switching may have a four-bundle structure of A-A-B-B-B-B-A-A. In FIGS. 4 to 7B, CLA may correspond to the red and blue pixel data and CLB may correspond to the green pixel data. As shown in a PDB area of FIG. 7A, the demux switching structure may be repeated in a unit of "A-A-B-B-B-B-A-A" (e.g., 200A-201A-201B-200B-199B-202B-202A-199A). For example, when the demux switching structure is repeated twice or more in the unit of "A-A-B-B-B-B-A-A-A-B-B-B-B-A-A . . ." In this case, except for a beginning part and an ending part, four of the data (the R data or the B data) corresponding to CLA are continuously disposed and four of the data (the G data) corresponding to CLB are continuously disposed so that the image quality deterioration due to the data coupling between

the data corresponding to CLA and the data corresponding to CLB may be relatively reduced.

For example, the data driver 500 includes first to fourth output amplifiers Y1, Y2, Y3 and Y4.

5 The demux circuit DXA may be connected to the first to fourth output amplifiers Y1, Y2, Y3, and Y4 to branches them into first to eighth output lines through demux switching.

For example, the first, fourth, fifth and eighth output lines 10 of the demux circuit DXA may be activated by the first switching signal CLA and the second, third, sixth and seventh output lines of the demux circuit DXA may be activated by the second switching signal CLB.

In the structure of FIG. 7A, the data corresponding to 15 CLA and the data corresponding to CLB may be in alternating pairs (e.g. 201A-201B-200B-200A-202A-202B-199B-199A). When an order of third data which are data at an input terminal of the demux circuit DXA is 1, 2, 3, 4, 5, 6, 7 and 8, an order of fourth data which are data at an output 20 terminal of the demux circuit DXA is 1, 2, 4, 3, 5, 6, 8 and 7.

The wire mixing structure is connected to the demux circuit DXA. The display panel 100 includes data lines connected to the wire mixing structure.

25 In the present embodiment, when first data is provided at an input terminal PDA of the wire mixing structure in the order of 1, 2, 3, 4, 5, 6, 7 and 8, the order of second data at an output terminal PDB of the wire mixing structure may be 4, 1, 2, 3, 7, 6, 5 and 8 as shown in FIG. 7A.

30 As shown in FIG. 4, the first output amplifier Y1 may alternately output the B data and the G data. The second output amplifier Y2 may alternately output the R data and the G data.

In FIG. 5, the display panel 100 may include a dummy 35 area DA, a border reduction area BA, a normal-border reduction area NBA and a normal area NA. A dummy data line DM may be disposed in the dummy area DA. Although one dummy data line DM is disposed in the dummy area DA in FIG. 5, the present inventive concept may not be limited thereto.

40 1A data line to 200A data line and 1B data line to 200B data line may be disposed in the border reduction area BA. Although four hundred data lines are disposed in the border reduction area BA in FIG. 5, the present inventive concept may not be limited thereto.

The 1A to 200A data lines and the 1B to 200B data lines in the border reduction area BA may receive data through a first border reduction line BRSA and a second border reduction line BRSB. The first border reduction line BRSA and the second border reduction line BRSB may be non-parallel, for example perpendicular to each other.

45 Two power applying lines EOA may be disposed between two adjacent data lines in the border reduction area BA. However, no power applying line may be disposed between other two adjacent data lines in the border reduction area BA. For example, the power applying line EOA may not be disposed between the 1A data line and the 1B data line. In contrast, two power applying lines EOA may be disposed between the 1B data line and the 2B data line. The power 50 applying line EOA may apply a low power voltage to the pixels.

55 201A data line to 400A data line and 201B data line to 400B data line may be disposed in the normal-border reduction area NBA. Although four hundred data lines are disposed in the normal-border reduction area NBA in the embodiment of FIG. 5, the present inventive concept may not be limited thereto. The data lines in the normal-border

reduction area NBA may receive data not through the first border reduction line BRSB and the second border reduction line BRSB but directly from the data driver 500. The first border reduction line BRSB is disposed in the normal-border reduction area NBA so that the data may be transmitted to the border reduction area BA through the second border reduction line BRSB.

In the normal-border reducing area NBA, a portion of the power applying line EOA may form the first border reduction line BRSB. When the portion of the power applying line EOA is used as the first border reduction line BRSB, the portion of the power applying line EOA used as the first border reduction line BRSB and another portion of the power applying line EOA that is not used as the first border reduction line BRSB may be insulated from each other. The portion of the power applying line EOA used as the first border reduction line BRSB may not transmit the low power voltage and the portion of the power applying line EOA that is not used as the first border reduction line BRSB may transmit the low power voltage.

401A data line to 540A data line and 401B data line to 540B data line may be disposed in the normal area NA. Although two hundred and eighty data lines are disposed in the normal area NA in FIG. 5, the present inventive concept may not be limited thereto. The data lines in the normal area NA may receive data not through the first border reduction line BRSB and the second border reduction line BRSB but directly from the data driver 500. In addition, the first border reduction line BRSB may not be disposed in the normal area NA. Accordingly, the power application line EOA in the normal area NA may be used only to apply the low power voltage.

The display panel 100 shown in FIG. 5 may correspond to half of an entire display area and the display panel 100 may be symmetric with respect to a center line CL.

As shown in FIG. 5, the display panel 100 may include a first power applying line, the 1A data line 1A, the 1B data line 1B, a second power applying line, a third power applying line, the 2B data line 2B, the 2A data line 2A and a fourth power applying line that are sequentially disposed.

First color data are applied to the 1A data line 1A, second color data are applied to the 1B data line and 2B data line and third color data applied to the 2A data line. For example, the first color data may be blue data, the second color data may be green data and the third color data may be red data.

As shown in FIG. 6, the display panel 100 may include a first color first light emitting area B11, a second color first light emitting area G11, a third color first light emitting area R11, a second color second light emitting area G12, a third color second light emitting area R21, a second color third light emitting area G21, a first color second light emitting area B21 and a second color fourth light emitting area G22.

Referring to FIGS. 6 and 7A, the 1A data line 1A of FIG. 7A may apply the first color data (e.g. the blue data) and the 1A data line 1A may be connected to the first color first light emitting area B11 of FIG. 6 and the first color second light emitting area B21 of FIG. 6. The 1B data line 1B of FIG. 7A may apply the second color data (e.g. the green data) and the 1B data line 1B may be connected to the second color first light emitting area G11 of FIG. 6 and the second color third light emitting area G21 of FIG. 6. The 2B data line 2B of FIG. 7A may apply the second color data (e.g. the green data) and the 2B data line 2B may be connected to the second color second light emitting area G12 of FIG. 6 and the second color fourth light emitting area G22 of FIG. 6. The 2A data line 2A of FIG. 7A may apply the third color data (e.g. the red data) and the 2A data line 2A may be

connected to the third color first light emitting area R11 of FIG. 6 and a third color third light emitting area R22 of FIG. 6.

Although not shown in the figures, a first color third light emitting area B12 of FIG. 6 may be disposed adjacent to the 2A data line 2A of FIG. 7A and the first color third light emitting area B12 of FIG. 6 may be connected to 3A data line applying the first color data (e.g. the blue data).

In addition, the third color second light emitting area R21 of FIG. 6 may be connected to the dummy data line DM of FIG. 7A.

For example, the second color first light emitting area G11 and the second color second light emitting area G12 may be disposed in a 1-1 row, the first color first light emitting area B11 and the third color first light emitting area R11 may be disposed in a 1-2 row adjacent to the 1-1 row, the second color third light emitting area G21 and the second color fourth light emitting area G22 may be disposed in a 2-1 row adjacent to the 1-2 row and the third color second light emitting area R21 and the first color second light emitting area B21 may be disposed in a 2-2 row adjacent to the 2-1 row.

Herein, four pixels of the second color first light emitting area G11, the first color first light emitting area B11, the second color third light emitting area G21 and the third color first light emitting area R11 may be disposed in a diamond shape. Similarly, four pixels of the second color second light emitting area G12, the third color first light emitting area R11, the second color fourth light emitting area G22 and the first color third light emitting area B12 may be disposed in a diamond shape. Similarly, four pixels of the third color first light emitting area R11, the second color third light emitting area G21, the first color second light emitting area B21 and the second color fourth light emitting area G22 may be disposed in a diamond shape.

Some of output data of the data driver 500 may be normal data NORMAL which are directly applied to the data line DL of the display panel 100 and some of the output data of the data driver 500 may be border reduction data BRS which are applied to the data line DL of the display panel 100 through the border reduction line BRSB.

For example, when an order of the first data which are data at an input terminal PDA of the wire mixing structure is 1, 2, 3, 4, 5, 6, 7 and 8, the first data (e.g. 201A, 201B, 202A and 202B of FIG. 7A) having an order of 1, 2, 5 and 6 are the normal data NORMAL and the first data (e.g. 200B, 200A, 199B and 199A of FIG. 7A) having an order of 3, 4, 7 and 8 are the border reduction data BRS.

In the present embodiment, the data corresponding to 1 to 200 data lines may be border reduction data BRS. In contrast, the data corresponding to 201 to 540 data lines may be the normal data NORMAL.

As shown in FIG. 7B, the input terminal PDA of the wire mixing structure may include first to eight A pads A1 to A8 that are sequentially disposed and the output terminal PDB of the wire mixing structure may include first to eight B pads B1 to B8 that are sequentially disposed.

As depicted in FIG. 7B, the first A pad A1 may be connected to the second B pad B2, the second A pad A2 may be connected to the third B pad B3, the third A pad A3 may be connected to the fourth B pad B4, the fourth A pad A4 may be connected to the first B pad B1, the fifth A pad A5 may be connected to the seventh B pad B7, the sixth A pad A6 may be connected to the sixth B pad B6, the seventh A pad A7 may be connected to the fifth B pad B5 and the eighth A pad A8 may be connected to the eighth B pad B8. According to the above explained wire mixing structure,

when the order of the first data at the input terminal PDA of the wire mixing structure is 1, 2, 3, 4, 5, 6, 7 and 8, the order of the second data at the output terminal PDB of the wire mixing structure may be 4, 1, 2, 3, 7, 6, 5 and 8.

Prior to the wire mixing structure, the data corresponding to CLA and the data corresponding to CLB may be alternately disposed in twos (e.g. 201A-201B-200B-200A-202A-202B-199B-199A). After the wire mixing structure, the data corresponding to CLA and the data corresponding to CLB may be alternately disposed in fours (e.g. 200A-201A-201B-200B-199B-202B-202A-199A) as shown in FIG. 7A. The four-bundle structure may be implemented by the wire mixing structure, and the data mapping error may be prevented in the four-bundle structure by the wire mixing structure.

FIG. 8 is a conceptual diagram illustrating an output amplifier of the data driver 500 for outputting a dummy data to a dummy data line DM of the display panel 100 of FIG. 1, the demux circuit and the display panel 100 of FIG. 1.

Referring to FIGS. 1 to 8, the data driver 500 may further include an N+1-th output amplifier (e.g. Y401), an N+2-th output amplifier (e.g. Y402), an N+3-th output amplifier (e.g. Y403), an N+4-th output amplifier (e.g. Y404), an N+5-th output amplifier (e.g. Y405), an N+6-th output amplifier (e.g. Y406), an N+7-th output amplifier (e.g. Y407) and an N+8-th output amplifier (e.g. Y408). Herein, the N+1-th output amplifier (e.g. Y401) may output the blue data and the green data, the N+2-th output amplifier (e.g. Y402) may output the red data and the green data, the N+3-th output amplifier (e.g. Y403) may output the red data and the green data, the N+4-th output amplifier (e.g. Y404) may output the blue data and the green data, the N+5-th output amplifier (e.g. Y405) may output the blue data and the green data, the N+6-th output amplifier (e.g. Y406) may output the red data and the green data, the N+7-th output amplifier (e.g. Y407) may output the red data and the green data and the N+8-th output amplifier (e.g. Y408) may output the blue data and the green data.

For example, the 401A to 540A data lines and the 401B to 540B data lines may be disposed in the normal area NA.

For example, the N+1-th output amplifier (e.g. Y401) may output data of (N+1)A data line (e.g. the 401A data line) and data of (N+1)B data line (e.g. the 401B data line) and the N+2-th output amplifier (e.g. Y402) may output data of the dummy data line DM.

In other words, the N+1-th output amplifier (e.g. Y401) may be used for outputting the normal data to the normal area NA and the N+2-th output amplifier (e.g. Y402) may be used for outputting the data of the dummy data line DM.

In addition, the N+3-th output amplifier (e.g. Y403), the N+4-th output amplifier (e.g. Y404) and the N+5-th output amplifier (e.g. Y405) may be inactive for a predefined period. In the present embodiment, the dummy data line DM may be connected to the red pixel and may correspond to the border reduction data BRS. Thus, one output amplifier group including four output amplifiers (a first amplifier outputting blue normal data and green normal data, a second amplifier outputting red border reduction data and green border reduction data, a third amplifier outputting red normal data and green normal data and a fourth amplifier including blue border reduction data and green border reduction data) may be used to output the red color border reduction data BRS so that the N+2-th output amplifier (e.g. Y402) may be activated to output the red border reduction data to the dummy data line DM connected to the red pixel but the N+3-th output amplifier (e.g. Y403), the N+4-th output amplifier

(e.g. Y404) and the N+5-th output amplifier (e.g. Y405) may be inactive for a predefined period.

The dummy data may be applied to the dummy data line DM through the first border reduction line and the second border reduction line that is connected to the first border reduction line which are disposed between the 400A data line and 401A data line.

In addition, the N+6-th output amplifier (e.g. Y406) may output data of (N+2)A data line (e.g. the 402A data line) and data of (N+2)B data line (e.g. the 402B data line), the N+7-th output amplifier (e.g. Y407) may output data of (N+3)A data line (e.g. the 403A data line) and data of (N+3)B data line (e.g. the 403B data line) and the N+8-th output amplifier (e.g. Y408) may output data of (N+4)A data line (e.g. the 404A data line) and data of (N+4)B data line (e.g. the 404B data line). The N+6-th output amplifier (e.g. Y406), the N+7-th output amplifier (e.g. Y407) and the N+8-th output amplifier (e.g. Y408) may output the normal data.

According to the present embodiment, the display apparatus may support the four-bundle demux switching structure and include the wire mixing structure for preventing the data mapping error so that the demux coupling may be enhanced and the data mapping error may be prevented.

In addition, the display apparatus may support the four-bundle demux switching structure without changing the integrated circuit of the data driver 500 and the active area of the display panel 100.

In addition, the data driver 500 may be formed in the border reduction structure in which the data voltage applied to the data line at the center of the display panel 100 and the data voltage applied to the data line at the edge of the display panel are alternatively outputted so that the dead space of the display apparatus may be reduced.

In addition, the demux circuit is disposed adjacent to the integrated circuit area on the second side of the bending line so that the dead space of the display apparatus may be further reduced.

In addition, the data driver 500 includes an element for applying the dummy data to the dummy data line DM so that the proper data may be applied to the dummy data line DM.

FIG. 9 is a conceptual diagram illustrating an output amplifier of a data driver 500 for outputting a dummy data to a dummy data line DM of a display panel 100 of a display apparatus according to an embodiment of the present inventive concept, a demux circuit and the display panel 100.

The display apparatus according to the present embodiment is substantially the same as the display apparatus of the previous embodiment explained referring to FIGS. 1 to 8 except for structures of an output amplifier of a data driver for outputting a dummy data, a demux circuit and a display panel. Thus, the same reference numerals will be used to refer to the same or like parts as those described in the previous embodiment of FIGS. 1 to 8 and any repetitive explanation concerning the above elements will be omitted.

Referring to FIGS. 1 to 7B and 9, the display apparatus includes the data driver 500, the demux circuit DXA, the wire mixing structure and the display panel 100. In the present embodiment, the demux switching may be a four-bundle structure of A-A-B-B-B-B-A-A. In FIGS. 4 to 7B, CLA may correspond to the red and blue pixel data and CLB may correspond to the green pixel data. As shown in a PDB area of FIG. 7A, the demux switching structure may be repeated in a unit of “A-A-B-B-B-B-A-A” (e.g., 200A-201A-201B-200B-199B-202B-202A-199A). For example, when the demux switching structure is repeated twice or more in the unit of “A-A-B-B-B-B-A-A-A-B-B-B-B”, the demux switching structure may be “A-A-B-B-B-B-A-A-A-B-B-B-B-

A-A . . ." In this case, except for a beginning part and an ending part, four of the data (the R data or the B data) corresponding to CLA are continuously disposed and four of the data (the G data) corresponding to CLB are continuously disposed so that the image quality deterioration due to the data coupling between the data corresponding to CLA and the data corresponding to CLB may be relatively reduced.

For example, the data driver 500 includes first to fourth output amplifiers Y1, Y2, Y3 and Y4.

The demux circuit DXA may cause the first to fourth output amplifiers Y1, Y2, Y3, and Y4 to branch into first to eighth output lines through demux switching.

For example, the first, fourth, fifth and eighth output lines of the demux circuit DXA may be activated by the first switching signal CLA and the second, third, sixth and seventh output lines of the demux circuit DXA may be activated by the second switching signal CLB as depicted in FIG. 7A.

In this structure, the data corresponding to CLA and the data corresponding to CLB may be alternately disposed in two (e.g. 201A-201B-200B-200A-202A-202B-199B-199A). When an order of third data which are data at an input terminal of the demux circuit DXA is 1, 2, 3, 4, 5, 6, 7 and 8, an order of fourth data which are data at an output terminal of the demux circuit DXA is 1, 2, 4, 3, 5, 6, 8 and 7.

The wire mixing structure is connected to the demux circuit DXA. The display panel 100 includes data lines connected to the wire mixing structure.

In the present embodiment, when an order of first data which are data at an input terminal PDA of the wire mixing structure is 1, 2, 3, 4, 5, 6, 7 and 8, an order of second data which are data at an output terminal PDB of the wire mixing structure may be 4, 1, 2, 3, 7, 6, 5 and 8 as depicted in FIG. 7A.

The data driver 500 may further include an N+1-th output amplifier (e.g. Y401), an N+2-th output amplifier (e.g. Y402), an N+3-th output amplifier (e.g. Y403), an N+4-th output amplifier (e.g. Y404), an N+5-th output amplifier (e.g. Y405), an N+6-th output amplifier (e.g. Y406), an N+7-th output amplifier (e.g. Y407) and an N+8-th output amplifier (e.g. Y408). Herein, the N+1-th output amplifier (e.g. Y401) may output the blue data and the green data, the N+2-th output amplifier (e.g. Y402) may output the red data and the green data, the N+3-th output amplifier (e.g. Y403) may output the red data and the green data, the N+4-th output amplifier (e.g. Y404) may output the blue data and the green data, the N+5-th output amplifier (e.g. Y405) may output the blue data and the green data, the N+6-th output amplifier (e.g. Y406) may output the red data and the green data, the N+7-th output amplifier (e.g. Y407) may output the red data and the green data and the N+8-th output amplifier (e.g. Y408) may output the blue data and the green data.

For example, the 401A to 540A data lines and the 401B to 540B data lines may be disposed in the normal area NA.

For example, the N+5-th output amplifier (e.g. Y405) may output data of (N+1)A data line (e.g. the 401A data line) and data of (N+1)B data line (e.g. the 401B data line) and the N+2-th output amplifier (e.g. Y402) may output data of the dummy data line DM.

In other words, the N+5-th output amplifier (e.g. Y405) may be used for outputting the normal data to the normal area NA and the N+2-th output amplifier (e.g. Y402) may be used for outputting the data of the dummy data line DM.

In addition, the N+1-th output amplifier (e.g. Y401), the N+3-th output amplifier (e.g. Y403) and the N+4-th output amplifier (e.g. Y404) may be inactive for a predefined

period. In the present embodiment, the dummy data line DM may be connected to the red pixel and may correspond to the border reduction data BRS. Thus, one output amplifier group including four output amplifiers (a first amplifier outputting blue normal data and green normal data, a second amplifier outputting red border reduction data and green border reduction data, a third amplifier outputting red normal data and green normal data and a fourth amplifier including blue border reduction data and green border reduction data) may be used to output the red color border reduction data BRS so that the N+2-th output amplifier (e.g. Y402) may be activated to output the red border reduction data to the dummy data line DM connected to the red pixel but the N+1-th output amplifier (e.g. Y401), the N+3-th output amplifier (e.g. Y403) and the N+4-th output amplifier (e.g. Y404) may be inactive for a predefined period.

The dummy data may be applied to the dummy data line DM through the first border reduction line and the second border reduction line that is connected to the first border reduction line which are disposed between the 400A data line and 401A data line.

In addition, the N+6-th output amplifier (e.g. Y406) may output data of (N+2)A data line (e.g. the 402A data line) and data of (N+2)B data line (e.g. the 402B data line), the N+7-th output amplifier (e.g. Y407) may output data of (N+3)A data line (e.g. the 403A data line) and data of (N+3)B data line (e.g. the 403B data line) and the N+8-th output amplifier (e.g. Y408) may output data of (N+4)A data line (e.g. the 404A data line) and data of (N+4)B data line (e.g. the 404B data line). The N+6-th output amplifier (e.g. Y406), the N+7-th output amplifier (e.g. Y407) and the N+8-th output amplifier (e.g. Y408) may output the normal data.

According to the present embodiment, the display apparatus may support the four-bundle demux switching structure and include the wire mixing structure for preventing the data mapping error so that the demux coupling may be enhanced and the data mapping error may be prevented.

In addition, the display apparatus may support the four-bundle demux switching structure without changing the integrated circuit of the data driver 500 and the active area of the display panel 100.

In addition, the data driver 500 may be formed in the border reduction structure in which the data voltage applied to the data line at the center of the display panel 100 and the data voltage applied to the data line at the edge of the display panel are alternatively outputted so that the dead space of the display apparatus may be reduced.

In addition, the demux circuit is disposed adjacent to the integrated circuit area on the second side of the bending line so that the dead space of the display apparatus may be further reduced.

In addition, the data driver 500 includes an element for applying the dummy data to the dummy data line DM so that the proper data may be applied to the dummy data line DM.

FIG. 10 is a block diagram illustrating an electronic apparatus according to an embodiment of the present inventive concept. FIG. 11 is a diagram illustrating an example in which the electronic apparatus of FIG. 10 is implemented as a smart phone.

Referring to FIGS. 10 and 11, the electronic apparatus 1000 may include a processor 1010, a memory device 1020, a storage device 1030, an input/output (I/O) device 1040, a power supply 1050, and a display apparatus 1060. Here, the display apparatus 1060 may be the display apparatus of FIG. 1. In addition, the electronic apparatus 1000 may further include a plurality of ports for communicating with a video

card, a sound card, a memory card, a universal serial bus (USB) device, other electronic apparatuses, etc.

In an embodiment, as illustrated in FIG. 11, the electronic apparatus **1000** may be implemented as a smart phone. However, the electronic apparatus **1000** is not limited thereto. For example, the electronic apparatus **1000** may be implemented as a cellular phone, a video phone, a smart pad, a smart watch, a tablet PC, a car navigation system, a computer monitor, a laptop, a head mounted display (HMD) device, and the like.

The processor **1010** may perform various computing functions or various tasks. The processor **1010** may be a micro-processor, a central processing unit (CPU), an application processor (AP), and the like. The processor **1010** may be coupled to other components via an address bus, a control bus, a data bus, etc. Further, the processor **1010** may be coupled to an extended bus such as a peripheral component interconnection (PCI) bus.

The processor **1010** may output the input image data **IMG** and the input control signal **CONT** to the driving controller **200** of FIG. 1.

The memory device **1020** may store data for operations of the electronic apparatus **1000**. For example, the memory device **1020** may include at least one non-volatile memory device such as an erasable programmable read-only memory (EPROM) device, an electrically erasable programmable read-only memory (EEPROM) device, a flash memory device, a phase change random access memory (PRAM) device, a resistance random access memory (RRAM) device, a nano floating gate memory (NFGM) device, a polymer random access memory (PoRAM) device, a magnetic random access memory (MRAM) device, a ferroelectric random access memory (FRAM) device, and the like and/or at least one volatile memory device such as a dynamic random access memory (DRAM) device, a static random access memory (SRAM) device, a mobile DRAM device, and the like.

The storage device **1030** may include a solid state drive (SSD) device, a hard disk drive (HDD) device, a CD-ROM device, and the like. The I/O device **1040** may include an input device such as a keyboard, a keypad, a mouse device, a touch-pad, a touch-screen, and the like and an output device such as a printer, a speaker, and the like. In some embodiments, the display apparatus **1060** may be included in the I/O device **1040**. The power supply **1050** may provide power for operations of the electronic apparatus **1000**. The display apparatus **1060** may be coupled to other components via the buses or other communication links.

FIG. 12 is a block diagram illustrating an electronic apparatus **101** according to an embodiment of the present inventive concept.

Referring to FIGS. 1 to 12, an electronic apparatus **101** outputs various information through a display module **140** in an operating system. When a processor **110** executes an application stored in a memory **120**, the display module **140** provides application information to a user through a display panel **141**.

The processor **110** obtains an external input through an input module **130** or a sensor module **161** and executes an application corresponding to the external input. For example, when the user selects a camera icon displayed on the display panel **141**, the processor **110** obtains a user input through an input sensor **161-2** and activates a camera module **171**. The processor **110** transfers image data corresponding to a captured image obtained through the camera module **171** to the display module **140**. The display module

140 may display an image corresponding to the captured image through the display panel **141**.

In an embodiment, when a personal information authentication is executed in the display module **140**, a fingerprint sensor **161-1** obtains input fingerprint information as input data. The processor **110** compares input data obtained through the fingerprint sensor **161-1** with authentication data stored in the memory **120**, and executes an application according to a comparison result. The display module **140** may display information executed according to application logic through the display panel **141**.

In an embodiment, when a music streaming icon displayed on the display module **140** is selected, the processor **110** obtains a user input through the input sensor **161-2** and activates a music streaming application stored in the memory **120**. When a music execution command is input in the music streaming application, the processor **110** activates a sound output module **163** to provide sound information corresponding to the music execution command to the user.

In the above, the operation of the electronic apparatus **101** is briefly described. Hereinafter, a configuration of the electronic apparatus **101** is described in detail. Some of elements of the electronic apparatus **101** described later may be integrated and provided as one element, or one element may be separated as two or more elements.

The electronic apparatus **101** may communicate with an external electronic apparatus **102** through a network (e.g. a short-range wireless communication network or a long-range wireless communication network). According to an embodiment, the electronic apparatus **101** may include the processor **110**, the memory **120**, the input module **130**, the display module **140**, a power module **150**, an embedded module **160**, and an external module **170**. According to an embodiment, in the electronic apparatus **101**, at least one of the above-described elements may be omitted or one or more other apparatus may be added. According to an embodiment, some of the above-described elements (e.g., the sensor module **161**, an antenna module **162** or the sound output module **163**) may be integrated into another element (e.g. the display module **140**).

The processor **110** may execute software to control at least one other element (e.g. hardware or software element) of the electronic apparatus **101** connected to the processor **110** and to perform various data processing or operations. According to an embodiment, as at least part of the data processing or the operations, the processor **110** may store receive instructions or data from other elements (e.g. the input module **130**, the sensor module **161** or a communication module **173**) in a volatile memory **121**, may process the instructions or data stored in the volatile memory **121** and may store result data of the processing in a nonvolatile memory **122**.

The processor **110** may include a main processor **111** and an auxiliary processor **112**. The main processor **111** may include at least one of a central processing unit (CPU) **111-1** and an application processor (AP). The main processor **111** may further include any one or more of a graphic processing unit (GPU) **111-2**, a communication processor (CP) and an image signal processor (ISP). The main processor **111** may further include a neural processing unit (NPU) **111-3**. The neural network processing unit **111-3** is a processor specialized in processing an artificial intelligence model. The artificial intelligence model may be generated through machine learning. The artificial intelligence model may include a plurality of artificial neural network layers. The artificial neural network may be one of a deep neural network (DNN), a convolutional neural network (CNN), a

recurrent neural network (RNN), a restricted boltzmann machine (RBM), a deep belief network (DBN), a bidirectional recurrent deep neural network (BRDNN) and a deep Q-networks or a combination of two or more of the above. However, the artificial neural network is not limited to the above examples. The artificial intelligence model may include software structures, in addition to hardware structures or instead of the hardware structures. At least two of the above-described processing units and the above-described processors may be implemented as an integrated element (e.g. a single chip) or each may be implemented as independent elements (e.g. in a plurality of chips).

The auxiliary processor 112 may include a controller. The controller may include an interface conversion circuit and a timing control circuit. The controller receives an image signal from the main processor 111, converts a data format of the image signal to meet interface specifications with the display module 140, and outputs image data. The controller may output various control signals for driving the display module 140.

The auxiliary processor 112 may further include a data converting circuit 112-2, a gamma correction circuit 112-3 and a rendering circuit 112-4. The data converting circuit 112-2 may receive the image data from the controller and may compensate the image data such that the image is displayed with a desired luminance according to characteristics of the electronic apparatus 101 or a user setting or may convert the image data to reduce a power consumption or compensate for afterimages. The gamma correction circuit 112-3 may convert the image data or a gamma reference voltage such that the image displayed on the electronic apparatus 101 has desired gamma characteristics. The rendering circuit 112-4 may receive the image data from the controller and may render the image data based on a pixel arrangement of the display panel 141 included in the electronic apparatus 101. At least one of the data converting circuit 112-2, the gamma correction circuit 112-3 and the rendering circuit 112-4 may be integrated into another element (e.g. the main processor 111 or the controller). At least one of the data converting circuit 112-2, the gamma correction circuit 112-3 and the rendering circuit 112-4 may be integrated into a data driver 143 to be described later.

The memory 120 may store various data used by at least one element (e.g. the processor 110 or the sensor module 161) of the electronic apparatus 101 and input data or output data for commands related thereto. The memory 120 may include at least one of the volatile memory 121 and the nonvolatile memory 122.

The input module 130 may receive commands or data used to the elements (e.g. the processor 110, the sensor module 161 or the sound output module 163) of the electronic apparatus 101 from the outside of the electronic apparatus 101 (e.g. the user or the external electronic apparatus 102).

The input module 130 may include a first input module 131 for receiving commands or data from the user and a second input module 132 for receiving commands or data from the external electronic apparatus 102. The first input module 131 may include a microphone, a mouse, a keyboard, a key (e.g. a button) or a pen (e.g. a passive pen or an active pen). The second input module 132 may support a designated protocol capable of connecting to the external electronic apparatus 102 by wire or wirelessly. According to an embodiment, the second input module 132 may include a high definition multimedia interface (HDMI), a universal serial bus (USB) interface, an SD card interface or an audio interface. The second input module 132 may include a

connector physically connected to the external electronic apparatus 102, for example, an HDMI connector, a USB connector, an SD card connector, or an audio connector (e.g. a headphone connector).

5 The display module 140 visually provides information to the user. The display module 140 may include the display panel 141, a scan driver 142 and the data driver 143. The display module 140 may further include a window, a chassis and a bracket to protect the display panel 141.

10 The display panel 141 may include a liquid crystal display panel, an organic light emitting display panel or an inorganic light emitting display panel. A type of the display panel 141 is not particularly limited. The display panel 141 may be a rigid type or a flexible type capable of being rolled or folded.

15 The display module 140 may further include a supporter or a heat dissipation member supporting the display panel 141.

The scan driver 142 may be mounted on the display panel 141 as a driving chip. Alternatively, the scan driver 142 may be integrated on the display panel 141. For example, the scan

20 driver 142 may include an amorphous silicon TFT gate driver circuit (ASG) integrated on the display panel 141, a low temperature polycrystalline silicon (LTPS) TFT gate driver circuit integrated on the display panel 141, or an oxide semiconductor TFT gate driver circuit (OSG) integrated on the display panel 141. The scan driver 142 receives a control signal from the controller and outputs the scan signals to the display panel 141 in response to the control signal.

The display module 140 may further include a light emission driver. The light emission driver outputs a light 30 emission control signal to the display panel 141 in response to a control signal received from the controller. The light emission driver may be formed independently from the scan driver 142. Alternatively, the light emission driver and the scan driver 142 may be integrally formed.

35 The data driver 143 receives a control signal from the controller and converts the image data into an analog voltage (e.g. the data voltage) and output the data voltages to the display panel 141 in response to the control signal.

The data driver 143 may be integrated into another 40 element (e.g. the controller). The functions of the interface conversion circuit and the timing control circuit of the controller described above may be integrated into the data driver 143.

The display module 140 may further include a voltage 45 generating circuit. The voltage generating circuit may output various voltages for driving the display panel 141.

The power module 150 supplies power to elements of the electronic apparatus 101. The power module 150 may include a battery which supplies a power voltage. The battery may include a non-rechargeable primary cell, a rechargeable secondary cell or a fuel cell. The power module 150 may include a power management integrated circuit (PMIC). The PMIC supplies optimized power to each of the above-described modules and modules described later. The power module 150 may include a wireless power transmission/reception member electrically connected to the battery. The wireless power transmission/reception member may include a plurality of antenna radiators in a form of coils.

The electronic apparatus 101 may further include the 60 embedded module 160 and the external module 170. The embedded module 160 may include the sensor module 161, the antenna module 162 and the sound output module 163. The external module 170 may include the camera module 171, a light module 172 and the communication module 173.

65 The sensor module 161 may detect an input by a user's body or an input by the pen among the first input module 131, and generate an electrical signal or data value corre-

sponding to the input. The sensor module 161 may include at least one of the fingerprint sensor 161-1, the input sensor 161-2 and a digitizer 161-3.

The fingerprint sensor 161-1 may generate a data value corresponding to a user's fingerprint. The fingerprint sensor 161-1 may include one of an optical fingerprint sensor or a capacitive fingerprint sensor.

The input sensor 161-2 may generate data values corresponding to coordinate information of the input by the user's body or the input by the pen. The input sensor 161-2 generates a capacitance change due to an input as a data value. The input sensor 161-2 may detect an input by the passive pen or transmit/receive data to/from the active pen.

The input sensor 161-2 may measure biosignals such as blood pressure, moisture, or body fat. For example, when a user touches a part of his body to a sensor layer or a sensing panel and does not move for a certain period of time, the input sensor 161-2 may detect the biosignal based on a change in an electric field caused by the part of the body so that the display module 140 may output user's desired information.

The digitizer 161-3 may generate a data value corresponding to the coordinate information input by the pen. The digitizer 161-3 generates an amount of electromagnetic change by the input as a data value. The digitizer 161-3 may detect an input by the passive pen or transmit/receive data to/from the active pen.

At least one of the fingerprint sensor 161-1, the input sensor 161-2 and the digitizer 161-3 may be formed as a sensor layer on the display panel 141 through a continuous process. The fingerprint sensor 161-1, the input sensor 161-2 and the digitizer 161-3 may be disposed on the display panel 141. At least one of the fingerprint sensor 161-1, the input sensor 161-2 and the digitizer 161-3, for example, the digitizer 161-3, may be disposed under the display panel 141.

At least two or more of the fingerprint sensor 161-1, the input sensor 161-2 and the digitizer 161-3 may be integrated into the sensing panel through the same process. When at least two or more of the fingerprint sensor 161-1, the input sensor 161-2 and the digitizer 161-3 are integrated into the sensing panel, the sensing panel may be disposed between the display panel 141 and a window disposed over an upper surface of the display panel 141. According to an embodiment, the sensing panel may be disposed on the window. The present inventive concept may not be limited to a position of the sensing panel.

At least one of the fingerprint sensor 161-1, the input sensor 161-2 and the digitizer 161-3 may be embedded in the display panel 141. For example, at least one of the fingerprint sensor 161-1, the input sensor 161-2 and the digitizer 161-3 is formed simultaneously with the display panel 141 through a process of forming elements included in the display panel 141 (e.g. light emitting elements, transistors, etc.).

In addition, the sensor module 161 may generate an electrical signal or a data value corresponding to an internal state or an external state of the electronic apparatus 101. For example, the sensor module 161 may further include a gesture sensor, a gyro sensor, a barometric pressure sensor, a magnetic sensor, an acceleration sensor, a grip sensor, a proximity sensor, a color sensor, an IR (infrared) sensor, a biosensor, a temperature sensor, a humidity sensor or an illuminance sensor.

The antenna module 162 may include one or more antennas for transmitting a signal or power to outside or receiving a signal or power from outside. According to an embodiment,

the communication module 173 may transmit a signal to an external electronic apparatus or receive a signal from an external electronic apparatus through an antenna suitable for a communication method. An antenna pattern of the antenna module 162 may be integrated with an element of the display module 140 (e.g. the display panel 141) or the input sensor 161-2.

The sound output module 163 is a device for outputting sound signals to the outside of the electronic apparatus 101. For example, the sound output module 163 may include a speaker used for general purposes such as playing multimedia or recording and a receiver used exclusively for receiving a call. According to an embodiment, the receiver may be formed integrally with or separately from the speaker. A sound output pattern of the sound output module 163 may be integrated with the display module 140.

The camera module 171 may capture still images and moving images. According to an embodiment, the camera module 171 may include one or more lenses, an image sensor or an image signal processor. The camera module 171 may further include an infrared camera capable of determining a presence or an absence of a user, the user's location and the user's gaze.

The light module 172 may provide light. The light module 172 may include a light emitting diode or a xenon lamp. The light module 172 may operate in conjunction with the camera module 171 or operate independently.

The communication module 173 may support establishment of a wired or wireless communication channel between the electronic apparatus 101 and the external electronic apparatus 102 and communication through the established communication channel. The communication module 173 may include one or both of a wireless communication module such as a cellular communication module, a short-distance wireless communication module, or a global navigation satellite system (GNSS) communication module and a wired communication module such as a local area network (LAN) communication module, or a power line communication module. The communication module 173 may communicate with the external electronic apparatus 102 through a short-range communication network such as Bluetooth, WiFi direct or infrared data association (IrDA) or a long-distance communication network such as a cellular network, the Internet, or a computer network (e.g. LAN or WAN). The various types of communication modules 173 described above may be implemented as a single chip or may be implemented as separate chips.

The input module 130, the sensor module 161 and the camera module 171 may be used to control the operation of the display module 140 in conjunction with the processor 110.

The processor 110 outputs commands or data to the display module 140, the sound output module 163, the camera module 171 or the light module 172 based on the input data received from the input module 130. For example, the processor 110 may generate image data corresponding to input data applied through a mouse or an active pen, and output the generated image data to the display module 140 or the processor 110 may generate command data corresponding to the input data and output the generated command data to the camera module 171 or the light module 172. When input data is not received from the input module 130 for a certain period of time, the processor 110 converts an operation mode of the electronic apparatus 101 into a low power mode or a sleep mode so that a power consumption of the electronic apparatus 101 may be reduced.

The processor 110 outputs commands or data to the display module 140, the sound output module 163, the camera module 171 or the light module 172 based on sensed data received from the sensor module 161. For example, the processor 110 may compare authentication data applied by the fingerprint sensor 161-1 with authentication data stored in the memory 120, and then execute an application according to the comparison result. The processor 110 may execute commands or output corresponding image data to the display module 140 based on the sensed data sensed by the input sensor 161-2 or the digitizer 161-3. When the sensor module 161 includes a temperature sensor, the processor 110 may receive temperature data for the temperature measured from the sensor module 161 and may further perform luminance correction on the image data based on the temperature data.

The processor 110 may receive determined data about the presence or the absence of the user, the user's location and the user's gaze from the camera module 171. The processor 110 may further perform luminance correction on the image data based on the determined data. For example, the processor 110, which determines the presence or the absence of the user through an input from the camera module 171, may display image data having the luminance corrected by the data converting circuit 112-2 or the gamma correction circuit 112-3 to the display module 140.

Some of the above elements may be connected to each other through a communication method between peripheral devices such as a bus, a general purpose input/output (GPIO), a serial peripheral interface (SPI), a mobile industry processor interface (MIPI), or a ultra path interconnect (UPI) link to exchange signals (e.g. commands or data) with each other. The processor 110 may communicate with the display module 140 through an agreed interface. For example, the processor 110 may communicate with the display module 140 through any one of the above communication methods. The present invention may not be limited to the above communication methods.

The electronic apparatus 101 according to various embodiments disclosed in the disclosure may be various types of apparatuses. For example, the electronic apparatus 101 may include at least one of a portable communication apparatus (e.g. a smart phone), a computer apparatus, a portable multimedia apparatus, a portable medical apparatus, a camera, a wearable device and a home appliance. The electronic apparatus 101 according to the embodiment of the disclosure may not be limited to the aforementioned apparatuses.

For example, the display panel 100 of FIG. 1 may correspond to the display panel 141 of FIG. 12. For example, the driving controller 200 of FIG. 1 may correspond to the controller of the auxiliary processor 112 of FIG. 12. For example, the gate driver 300 of FIG. 1 may correspond to the scan driver 142 of FIG. 12. For example, the data driver 500 of FIG. 1 may correspond to the data driver 143 of FIG. 12.

According to the display apparatus in the present inventive concept, the demux coupling may be enhanced and the data mapping error may be prevented.

The foregoing is illustrative of the present inventive concept and is not to be construed as limiting thereof. Although a few embodiments of the present inventive concept have been described, those skilled in the art will readily appreciate that many modifications are possible in the embodiments without materially departing from the novel teachings and advantages of the present inventive concept. Accordingly, all such modifications are intended to be included within the scope of the present inventive concept as

defined in the claims. In the claims, any means-plus-function clauses are intended to cover the structures described herein as performing the recited function and not only structural equivalents but also equivalent structures. Therefore, it is to be understood that the foregoing is illustrative of the present inventive concept and is not to be construed as limited to the specific embodiments disclosed, and that modifications to the disclosed embodiments, as well as other embodiments, are intended to be included within the scope of the appended claims. The present inventive concept is defined by the following claims, with equivalents of the claims to be included therein.

What is claimed is:

1. A display apparatus comprising:
a data driver including four output amplifiers;
a demux circuit connected to the four output amplifiers
and branching the four output amplifiers into first,
second, third, fourth, fifth, sixth, seventh, and eighth
output lines through demux switching;

a wire mixing structure connected to the demux circuit,
the wire mixing structure having an input terminal and
an output terminal; and
a display panel including data lines connected to the wire
mixing structure,

wherein first data being provided to the input terminal of
the wire mixing structure in an order of 1, 2, 3, 4, 5, 6,
7 and 8 produces second data in an order of 4, 1, 2, 3,
7, 6, 5 and 8 at the output terminal of the wire mixing
structure,

wherein output data from the data driver comprise at least
one of normal data that are directly applied to data lines
of the display panel, and

border reduction data that are applied to data lines of the
display panel through border reduction lines, and

wherein the first data having order numbers of 1, 2, 5 and
6 are the normal data and the first data having order
numbers of 3, 4, 7 and 8 are the border reduction data.

2. The display apparatus of claim 1, further comprising a
bending area disposed between the display panel and the
data driver,

wherein the demux circuit is disposed between an integrated
circuit area of the data driver and the bending area.

3. The display apparatus of claim 2, wherein the bending
area includes a bending line for folding elements toward a
rear surface of the display panel, and

wherein the display panel is disposed on a first side of the
bending line and the demux circuit and the integrated
circuit area are disposed on a second side of the
bending line.

4. The display apparatus of claim 1, wherein the first, the
fourth, the fifth and the eighth output lines of the demux
circuit are activated by a first switching signal, and

wherein the second, the third, the sixth and the seventh
output lines of the demux circuit are activated by a
second switching signal.

5. The display apparatus of claim 1, wherein the input
terminal of the wire mixing structure includes first to eighth
A pads that are sequentially disposed, and the output terminal
of the wire mixing structure includes first to eighth B
pads that are sequentially disposed,

wherein the first A pad is connected to the second B pad,
wherein the second A pad is connected to the third B pad,
wherein the third A pad is connected to the fourth B pad,
wherein the fourth A pad is connected to the first B pad,
wherein the fifth A pad is connected to the seventh B pad,
wherein the sixth A pad is connected to the sixth B pad,

23

wherein the seventh A pad is connected to the fifth B pad,
and

wherein the eighth A pad is connected to the eighth B pad.

6. The display apparatus of claim 1, wherein the data driver further comprises an N+1-th output amplifier, an N+2-th output amplifier, an N+3-th output amplifier, an N+4-th output amplifier, an N+5-th output amplifier, an N+6-th output amplifier, an N+7-th output amplifier and an N+8-th output amplifier,

wherein the N+1-th output amplifier is configured to output data of (N+1)A data line and data of (N+1)B data line, and

wherein the N+2-th output amplifier is configured to output data of a dummy data line.

7. The display apparatus of claim 6, wherein the N+3-th output amplifier, the N+4-th output amplifier and the N+5-th output amplifier are inactive for a predefined period.

8. The display apparatus of claim 7, wherein the N+6-th output amplifier is configured to output data of (N+2)A data line and data of (N+2)B data line,

wherein the N+7-th output amplifier is configured to output data of (N+3)A data line and data of (N+3)B data line, and

wherein the N+8-th output amplifier is configured to output data of (N+4)A data line and data of (N+4)B data line.

9. The display apparatus of claim 1, wherein the data driver further comprises an N+1-th output amplifier, an N+2-th output amplifier, an N+3-th output amplifier, an N+4-th output amplifier, an N+5-th output amplifier, an N+6-th output amplifier, an N+7-th output amplifier and an N+8-th output amplifier,

wherein the N+5-th output amplifier is configured to output data of (N+1)A data line and data of (N+1)B data line, and

wherein the N+2-th output amplifier is configured to output data of a dummy data line.

10. The display apparatus of claim 9, wherein the N+1-th output amplifier, the N+3-th output amplifier and the N+4-th output amplifier are inactive.

11. The display apparatus of claim 10, wherein the N+6-th output amplifier is configured to output data of (N+2)A data line and data of (N+2)B data line,

wherein the N+7-th output amplifier is configured to output data of (N+3)A data line and data of (N+3)B data line, and

wherein the N+8-th output amplifier is configured to output data of (N+4)A data line and data of (N+4)B data line.

12. The display apparatus of claim 1, wherein the display panel includes a first power applying line, a 1A data line, a 1B data line, a second power applying line, a third power applying line, a 2B data line, a 2A data line and a fourth power applying line which are sequentially disposed,

wherein first color data are applied to the 1A data line, wherein second color data are applied to the 1B data line and the 2B data line, and

wherein third color data are applied to the 2A data line.

13. The display apparatus of claim 12, wherein the display panel includes a first color first light emitting area, a second color first light emitting area, a third color first light emitting area, a second color second light emitting area, a third color

24

second light emitting area, a second color third light emitting area, a first color second light emitting area and a second fourth light emitting area,

wherein the 1A data line is connected to the first color first light emitting area and the first color second light emitting area,

wherein the 1B data line is connected to the second color first light emitting area and the second color third light emitting area,

wherein the 2B data line is connected to the second color second light emitting area and the second color fourth light emitting area, and

wherein the 2A data line is connected to the third color first light emitting area.

14. The display apparatus of claim 13, wherein the third color second light emitting area is connected to a dummy data line.

15. The display apparatus of claim 13, wherein the second color first light emitting area and the second color second light emitting area are disposed in an 1-1 row,

wherein the first color first light emitting area and the third color first light emitting area are disposed in an 1-2 row adjacent to the 1-1 row,

wherein the second color third light emitting area and the second color fourth light emitting area are disposed in a 2-1 row adjacent to the 1-2 row, and

wherein the third color second light emitting area and the first color second light emitting area are disposed in a 2-2 row adjacent to the 2-1 row.

16. The display apparatus of claim 1, wherein third data being provided to an input terminal of the demux circuit in an order of 1, 2, 3, 4, 5, 6, 7 and 8 produces fourth data at an output terminal of the demux circuit in an order of 1, 2, 4, 3, 5, 6, 8 and 7.

17. An electronic apparatus comprising:

a data driver including four output amplifiers;
a demux circuit connected to the four output amplifiers
and branching the four output amplifiers into eight
output lines through demux switching;

a wire mixing structure connected to the demux circuit,
the wire mixing structure having an input terminal and
an output terminal;

a display panel including data lines connected to the wire
mixing structure;

a driving controller configured to control the data driver;
and

a processor configured to output input image data and an
input control signal to the driving controller,

wherein first data being provided to the input terminal of
the wire mixing structure in an order of 1, 2, 3, 4, 5, 6,
7 and 8 produces second data in an order of 4, 1, 2, 3,
7, 6, 5 and 8 at the output terminal of the wire mixing
structure,

wherein output data from the data driver comprise at least
one of normal data that are directly applied to data lines
of the display panel, and

border reduction data that are applied to data lines of the
display panel through border reduction lines, and

wherein the first data having order numbers of 1, 2, 5 and
6 are the normal data and the first data having order
numbers of 3, 4, 7 and 8 are the border reduction data.
